UNITED STATES PATENT OFFICE

LOUIS E. FORD, OF BORGER, TEXAS

DESIGN FOR A COMBINED CIGARETTE HOLDER AND ASH RECEIVER

Application filed July 17, 1929. Serial No. 32,094. Term of patent 14 years.

To all whom it may concern:

Be it known that I, LOUIS E. FORD, a citizen of the United States, residing at Borger, in the county of Hutchinson and State of Texas, have invented a new, original, and ornamental Design for a Combined Cigarette Holder and Ash Receiver, of which the following is a specification, reference being had to the accompanying drawing, forming part thereof.

Figure 1 is a side elevation of a combined cigarette holder and ash receiver, showing my new design, and

I claim:

The ornamental design for a combined cigarette holder and ash receiver, as shown.

LOUIS E. FORD.
